Application June 8, 1949, Serial No. 97,868

4 Claims. (Cl. 2—14)

(Granted under the act of March 3, 1883, as
amended April 30, 1928; 370 O. G. 757)

1

The invention described herein, if patented, may be manufactured and used by or for the Government for governmental purposes without the payment to us of any royalty thereon.

This invention relates to anti-fogging and anti-frosting goggles and, more particularly, to goggles of the double-lens type, provided with an improved closed air circulating system for removing moisture from the air and preventing the collection thereof upon the goggle lenses.

In order to provide a goggles structure which may be utilized under low ambient temperature conditions, it is necessary to provide an air-circulatory system for the goggles which keeps the goggle lenses free of moisture and at the same time prevents undue chilling of the eyes.

Accordingly, it is an object of this invention to provide a new and improved flexible anti-fogging and anti-frosting goggles.

Further, it is an object of this invention to provide a flexible goggles structure having improved dehumidifying and air cooling means for the air in the eyecup cavities of the goggles to prevent fogging or frosting of the lens thereof in cold weather.

It is another object of this invention to provide a flexible goggles having one or more condensers for cooling and dehumidifying the air in the eyecups by circulation of air through the condensers so that undue chilling of the eyes is prevented.

Further objects, advantages, adaptations and modifications of this invention will be apparent from the following description and the accompanying drawings, wherein:

Figure 1 is a front elevation of the goggles structure embodying this invention;

Figure 2 is a cross-sectional view on the line 2—2 of Fig. 1;

Figure 3 is a vertical transverse cross-sectional view of the condenser structure embodied in this invention; and

Figure 4 is a partial top plan view with one of the condenser elements partially broken away.

Referring to the drawings, goggles frame 10 comprises a conventional, flexible, rubber-type structure having a resilient, face-contacting part 11, a circumferential web 12, provided with bead 13, within which is a flexible lens-holding groove 14.

As above indicated, the goggles frame 10 is of conventional rubber material, and the groove 14 is adapted to be flexed for insertion of goggles lens 15 in the usual and conventional manner. In addition to the groove 14, there are provided conventional snap fasteners 16, likewise of conven-

2

tional structure for clamping or securing the lens 15 in groove 14. Goggles frame 10 is also provided with a conventional head-strap 17, threaded through and fastened to lugs or ears 18 in a conventional manner.

The face-contacting side of the face-contacting part 11 of the goggles frame is overlaid with a layer of chamois or cloth 11' and the lower portion of this coating is extended to provide a nose protector 19. Any suitable rubber cellulosic or resinous adhesive may be used to secure this covering to the part 11 of the frame.

Attached across the top of the goggles frame 10, as shown in Fig. 1, is a series of closed, condensers 20 formed from heat conductive metal in the nature of copper, aluminum, tin or the like. These condensers 20 comprise rectangular, box-like structures formed from thin, flexible copper sheeting 21. The front, top and side walls may be formed from a single sheet provided with a series of internal accordion folds at spaced intervals to provide the uniformly spaced internal fins 22 in the condensers 20. The housing is completed by sheet copper end walls 23 having vertical flanges 23' overlapping the peripheral edges of the front and back walls and sealed thereto by soldering or by use of a suitable adhesive, in the nature of rubber, cellulose acetate or the like, making condenser 20 open only at its lower end, as shown in Fig. 3.

Within condenser 20 is provided a partition 24, consisting of a longitudinal thin copper sheet of the same width as the front wall and bent to form a series of fins 25, which project into the space between fins 22 when the parts are in assembled relation. The lower end 24' of the partition 24 is bent upon itself and hooked to form a U-shaped clamp 26, which fits about a cork or rubber insulating ring 27, shown in Figs. 2 and 3 to hold the latter and a transparent partition 28 in spaced relation to the lens 15.

The insulation 27 is secured about the upper edge of the partition 28. Further, this insulation 27 is secured to the partition 24, in the manner indicated, and cemented to web 12 by suitable rubber, cellulose or plastic adhesive, in spaced relationship to the lens 15. Spacer elements 29, consisting of suitable flexible material, in the nature of cork or rubber blocks, are likewise adhesively secured to the web 12 and to lens 28.

In order to secure the condensers 20 within the web portion 12 of goggles frame 10, a plurality of rectangular openings 30 corresponding in area substantially to the horizontal cross-sectional area of condensers 20 are cut through the web 12

so that the open lower end portion of the condensers 20 may be placed therein and sealed against the leakage of air by a suitable adhesive, as rubber, resin or the like.

As disclosed in Fig. 3, the bottom edge of the front walls of condensers 20 is sealed or cemented against the bead 13 at 31 and the bottom edge of the rear wall is sealed to the portion 11 of the goggles frame 10 at 32. The end walls 23 of the condensers may likewise be cemented to the opposite ends of openings 30.

With an arrangement of the structure as described and the goggles suitably adjusted against the face of the wearer, normal body heat will cause convection currents within the eyecup cavities and the condensers 20. The air in the eyecup cavities, due to its relatively elevated temperature, will pass from about the eyes upwardly into the condensers 20. The condensers 20, being exposed to climatic temperatures and conditions, provides condensation surfaces for moisture contained in the air passing therethrough. That is, under low temperature conditions moisture condenses and solidifies on the heat-conducting surfaces within the condensers 20 as air passes through the tortuous passageway provided by fins 22 and 25 upwardly and downwardly over partition 24. With the air thus relieved of moisture content and cooled, it flows downwardly between the lens 15 and transparent partition 28. The lower edge of this partition 28 is spaced from the lower inner edge of the frame 10 to define an opening 33 through which air from the space between the lens 15 and partition 28 passes to re-absorb further moisture which may develop within the eyecup cavity between partition 28 and the wearer's eyes.

It will be observed therefore that there has been provided a flexible goggles structure capable of withstanding low temperature conditions of 0° F. and somewhat lower for relatively unlimited periods of time.

In accordance with the patent statutes, the foregoing is a description in detail of what is now considered to be the preferred form of the invention, but it will be obvious that various minor changes may be made in the structural details without departing from the spirit of the invention, and it is intended that all such changes be included within the scope of the appended claims.

We claim:

1. In an anti-fogging and anti-frosting goggles having a lens supported in a frame which has a flexible face-contacting part cooperating with the lens to define a substantially sealed space around the eyes of a wearer the combination comprising, one or more air cooling and dehumidifying condensers sealed in apertures in one side of said frame, said condensers each comprising a housing having horizontal and vertical partitioning means defining front and rear tortuous passages communicating with each other at the ends thereof adjacent the outer end of the housing and with the sealed space encompassed by said frame adjacent their opposite ends; and air deflecting means cooperating with the partitioning means to isolate the inner ends of the front and rear passages from direct communication with each other, said deflecting means, partitioning means and lens also cooperating to promote convectional flow of air from the space in said goggles containing air warmed by contact with the wearer's face through the condensers and adjacent the inner side of the

lens back to the said warmed air space in the goggles at a region opposite the condensers.

2. In an anti-fogging and anti-frosting goggles having a lens supported in a frame which has a flexible face-contacting part cooperating with the lens to define a substantially sealed space around the eyes of a wearer the combination comprising, one or more condensers sealed in apertures in one side of said frame, said condensers each comprising a housing having horizontal and vertical partitioning means defining front and rear tortuous passages communicating with each other at the ends thereof adjacent the outer end of the housing and with the sealed space encompassed by said frame adjacent their opposite ends; and a transparent partition in said frame cooperating with the lens to define a relatively narrow space immediately behind said lens communicating with the space behind the partition containing air warmed by contact with the wearer's face at the side of the frame opposite said condenser, said transparent partition cooperating with the partitioning means in the condenser to promote convectional flow of air from the warm air space through the condenser and from the discharge side of the latter through the narrow space and back to the warm air space.

3. In an anti-fogging and anti-frosting goggles having a lens supported in a frame which has a flexible face-contacting part cooperating with the lens to define a substantially sealed space around the eyes of a wearer the combination comprising, one or more condensers sealed in one side of said frame, each of said condensers comprising a generally rectangular box-like housing of relatively thin sheet material bent to form a plurality of fins projecting horizontally and vertically relative to the side wall of said housing, a partition in said housing having a plurality of fins thereon, said partition and the fins thereon and on said housing cooperating to define tortuous front and rear passages communicating with each other at the ends thereof adjacent the outer end of the housing and with the sealed space encompassed by said frame adjacent their opposite ends; and air deflector means cooperating with the partitioning means to isolate the lower ends of the front end rear passages from direct communication with each other, said deflector means, partitioning means and lens also cooperating to promote convectional flow of air from the space in said goggles containing air warmed by contact with the wearer's face through the condenser and along the inner side of the lens back to the said warmed air space in the goggles at a region opposite the condenser.

4. In an anti-fogging and anti-frosting goggles having a lens supported in a frame including a flexible face-contacting part cooperating with the lens to define a substantially sealed space around the eyes of a wearer the combination comprising, one or more condensers sealed in the top side of said frame, said condensers each comprising a housing and partitioning means to divide the housing into vertical passages communicating with each other at the ends thereof adjacent the upper end of the housing and with the space encompassed by said frame adjacent their opposite ends; and a transparent partition in said frame cooperating with the lens to define a relatively narrow space immediately behind said lens communicating with the space behind the partition containing air warmed by contact with

the wearer's face adjacent the lower edge of the frame, the lower edge of the partitioning means in said condenser being hooked and embracing the portion of the upper edge of the transparent partition coextensive therewith, and a gasket between the transparent partition and hooked end of the partitioning means, said transparent partition cooperating with the partitioning means in the condenser to promote convectional flow of air from the warmed air space through the condensers and from the discharge side of the latter through the closed space and back to the warm air space.
